GROUTING SYSTEM

Ray L. Allin, San Francisco, Calif.

Application June 29, 1940, Serial No. 343,100

3 Claims. (Cl. 72—106)

My invention relates to a new system and apparatus for introducing suitable grout into contraction joints of concrete structures in the course of their erection, or, preferably after their completion, and to provide a direct method of forcing the grouting material into and along the contraction joints, and to avoid the attendant difficulties, uncertainties, poor quality of grout, and great expense caused by the use of the present methods and available equipment.

Concrete contracts in setting and as it dries out and cools off it shrinks to such extent that large concrete structures will develop cracks that may form at such positions and locations as to be dangerous to the stability of the structure. By locating contraction joints in the structure at frequent intervals and at proper positions and locations, the development of dangerous cracks can be entirely eliminated. To strengthen the concrete structure due to the weakening effect of the contraction joints, the contraction joints are filled with Portland cement grout or other suitable cementing material, forced into and along the contraction joint under pressure, preferably when the structure is at its lowest temperature and when the structure has the least external load to be carried by it. The grouting of the vertical, normal contraction joints in concrete structures, such as retaining walls and dams, is very important, and in such structures arched in plan and depending on arch action for stability, grouting of the vertical radial and circumferential joints is of the greatest importance; and it is advisable to do the grouting at an estimated pressure such that when the maximum loads are imposed on the structure, there will be practically no tensile stresses remaining in the structure. In grouting the contraction joints of such structures it is very important to provide means for the direct removal of water, foreign matter and the advancing sheet of grout which usually gets so mixed with foreign matter that it loses its strength and becomes of a chalky weak character unsuited for binding the structure together as a monolith. By providing means to withdraw this poor grade of grout from all parts of the joint and continuing to force good grout into the joint until only good grout emerges from the joint vent system, insures that the joint has only good grout in it over its entire area. This method of grouting of the contraction joints between the various parts of such structures, cements the parts into a monolithic structure, which will transmit arch thrusts to the rock abutments

on each side of the canyon with practically no tension stresses in the structure.

During the grouting of any contraction joint in the structure it is very important to force water into all joints not already grouted, and to maintain the water in these joints at the constant pressures at which they will later be grouted.

My invention contemplates the use of any system of operative procedure in the accomplishment of these results and any arrangement of open conduits attached to the face of the concrete forming the contraction joint, and by any system of open conduits which provides means for forcing the cementing fluid in one group of open conduits to be designated the injection conduits, and withdrawing or venting the fluid after it has passed into and through the contraction joint opening and on into and through another group of open conduits to be designated the vent conduits; the two groups so located and so arranged as to insure the forcing in and retaining of good grout in all parts of the contraction joint.

25 The objects of my invention are:

First; to provide an open conduit system and apparatus for grouting the contraction joints which will occur between different parts of a concrete structure of large dimensions such as a massive concrete dam or retaining wall in which one or more parts or units of the structure are built up progressively to partial or full height and allowed to harden in advance of the other parts or units of the structure, which are later poured against the formed faces of the parts or units first built.

Second; to provide an open conduit system and apparatus for grouting concrete structures whereby the shrinkage and temperature openings or cracks designated as contraction joints developing between the different parts or units of the structure, which have been poured at different times, are grouted under pressure with cement grout and strongly bonded to form them into one integral whole.

Third; to provide a simple, inexpensive, easily erected grouting system of sufficiently rigid construction to remain in place while the concrete structure is being poured and will be effective in thoroughly filling the opening in all contraction joints when the pressure grouting operation is performed.

Fourth; to provide an open conduit supplying, injecting, distributing, venting, grout system and apparatus which can be progressively installed

unit by unit as the forms for each successive vertical increment of a large concrete unit are erected upon and above the concrete previously poured and hardened, and thereby avoiding any necessity of following any special erection and construction programs from those which would be followed were a grouting mechanism not used.

Fifth; to provide a plurality of open injection and venting conduits communicating independently between predetermined positioned points into the space to be grouted or filled and the outside source of supply where the grouting material is introduced under pressure, with said plurality of communicating open conduits entirely embedded between the face of the concrete first poured and hardened, and the face of the second pour; the corrugations of the concrete in the joint in the first pour protecting the injection and venting conduits from injury during the making of the second pour.

Other objects and features of advantage will be apparent during the course of the following description.

In the accompanying drawings forming part of this specification and in which like numerals are employed to designate like parts throughout the same,

Figure 1 is a vertical sectional view, showing a portion of the formed concrete face of the contraction joint forming a unit or part of the concrete structure, in connection with a grout supplying open header conduit 1, an open riser conduit 2, through both of which grout is forced into and along the contraction joint.

Figure 2 is a vertical sectional view of a portion of two finished and hardened concrete units, showing the contraction joint opening H between the units, and the separated open header conduit and open riser conduit through which and out of which the grout can flow at all points along the open conduits into and along the contraction joint.

Figure 3 is a horizontal sectional view of a portion of the finished and hardened concrete unit, showing the open riser conduit 3 attached to the formed concrete face of the first poured concrete. This view is typical of a section taken normal to the axis of the open conduits used in the injection and venting conduits.

Figure 4 is a side view of a portion of a structural unit, showing a portion of the injection header conduit 1, injection riser conduit 2, and pipe connection 4 leading to the surface of the concrete passing to one side of grout stop 11. This view inverted is also typical of the side view of a vent header conduit and vent riser conduit and vent pipe connection.

Figure 5 is a horizontal sectional view of a portion of the finished and hardened concrete unit, showing an injection header conduit 1, and an injection pipe 4 leading to the surface of the concrete passing to one side of the grout stop 11. This view is also typical of a horizontal sectional view of the vent header conduit and vent pipe leading to the surface of the concrete.

Figure 6 is a vertical sectional view of a portion of the finished and hardened concrete unit, showing an injection riser conduit 2, an ejection riser pipe 6, and its connection to the open conduit 18, the upper header pipe 7 and its connection by T-22 to the injection riser pipe 6, and a 1 $\frac{1}{8}$ inch fillet welded lap-joint 30 showing method of connection at a reduction in size of angle conduits 2. This vertical sectional view inverted is also typical of the vent riser conduit, a vent riser pipe and

its connection to the vent riser conduit, the lower header pipe and its connection by T to the vent riser pipe and lap-joint.

Figures 7 and 7A are side views of a structural concrete unit, Figure 7 representing a typical grout panel at the bottom and Figure 7A a typical grout panel at the top of the structure, showing the injection header conduits 1, the injection riser conduits 2, riser vent conduits 3, injection pipe connections 4, vent header conduits 5, injection riser pipes 6, upper pipe header 7, vent riser pipes 8, lower pipe header 9, vent pipe connections 10 to the surface of the concrete, and grout stops 11, the unit having the appearance it presents when ready for the pouring of an adjoining unit or part of the concrete structure.

Figures 8 and 9 are plan views of portions of two concrete units or parts of the concrete structure showing the lower portion of the grouting system installed and fastened in place after the first and second units have hardened.

Figure 10 is a plan view of a portion of one concrete unit at a higher elevation than shown in Figures 8 and 9, showing the open conduits fastened to the concrete surface of one of the concrete units that has hardened.

Figure 11 is a plan view of a portion of one of the concrete units, showing the typical configuration of one of the side faces thereof in the central portion of the unit; these configurations are suppressed near the horizontal grout stops.

Figures 12 and 12A are vertical sectional views of a portion of the finished and hardened concrete unit, Figure 12 representing a typical sectional view of the bottom grout panel or panels, and Figure 12A a typical sectional view of the top grout panel or panels of the structure, showing the injection header conduits 1, injection riser conduits 2, riser vent conduits 3, vent header conduit 5, injection riser pipes 6, upper header pipe 7, vent riser pipe 8, lower header pipes 9, and grout stops 11; these views also show the typical configuration of one of the side faces of a concrete unit, with configurations suppressed near the horizontal grout stops.

Figure 13 is a horizontal sectional view of a fragment of a concrete-holding form, showing a metal strip secured to one side thereof which later closes the contraction joint opening between two adjoining concrete units.

Figure 14 is a horizontal sectional view of a portion of two hardened units and the joint-closing metal strip partially embedded therein.

Figure 15 is a plan view of fragments of two hardened units, showing the contraction joint opening between them and the joint-closing strip partially embedded in each unit; and a plastic filler strip inserted in the U of the joint-closing strip.

Referring now to the drawings, the apparatus I employ to accomplish the objects of my invention, consists of an open grout injection header conduit 1 which is placed horizontally or approximately so, near the lower confines or bottom edge portion of each of the contraction joints, being set preferably parallel thereto, and to this injection header conduit 1, I secure at predetermined distances apart along its length, the lower ends of injection riser conduits 2, which extend up vertically against and attached to the face of the concrete unit or block of concrete along which the contraction joint is to occur to the top surface of the completed structure. In the preferred construction of the injection and venting conduits, any suitable open conduits may be used,

the header conduits are preferably made of 2 inch by 2 inch by $\frac{1}{8}$ inch small steel angles, and the riser conduits are preferably made of 1 $\frac{1}{4}$ inch by 1 $\frac{1}{4}$ inch by $\frac{1}{8}$ inch small steel angles in the lower half of the riser, reducing in the upper half of the riser to 1 inch by 1 inch by $\frac{1}{8}$ inch small steel angles, and are made in any predetermined length, the header and riser conduits communicate through a suitable opening, preferably a triangular opening 12 in the leg of the header angles 1 and 5 respectively, and placing the bevel-cut end of the riser angles 2 and 3 respectively over the respective cut openings, and joining the two angles respectively by any suitable means that will prevent the entry of mortar at the joint, preferably by $\frac{1}{16}$ inch continuous fillet wells 13 on the outside surfaces of contact of the angles, the header and riser conduits held firmly against the smooth surface 14 of the previously poured and hardened unit of the concrete structure.

My invention contemplates the securing of these header and riser angles against the smooth surface 14 of the concrete by any suitable means; but I preferably secure them to the concrete face with 10-penny nails embedded in the previously poured concrete or similar suitable attachments substantially as shown in the accompanying drawings at A. I preferably have the vertical riser angles made in a number of units whose equal lengths are each equal to, or multiples of the vertical depths of concrete to be poured. The ends of two adjacent units being joined by any suitable means that will prevent the entry of mortar at the joint, preferably by $\frac{1}{16}$ inch continuous fillet welds on the outside surfaces of contact of the angles.

This unit method of assembly and emplacement is particularly well adapted to structures of the largest size and also permits making the lengths of the units composing the riser angles such that, if the structures wherein they are used be so great as to necessitate several successive pourings of concrete in vertical sequence, one above the other, these lengths will either singly or in multiples equal the amount that the concrete is raised in these progressive steps of pourings required to reach the final completed height of the structure. I hold the angles firmly against the smooth surface 14 of the concrete by any suitable means, preferably by steel wire ties 15, the looped ends of which are placed over the bent nail ends A and wire ties twisted together over the heel of the angle by means of a wire tying brace, or by twisting a nail inserted in the tie wire loops or other suitable means which presses the angles firmly against the smooth surface 14 and makes a strong rigid construction for the purpose intended, which can be built up readily as fast as the concrete is poured and hardened, and will remain fixed in the predeterminedly selected and erected positions while the concrete is poured against the smooth surface 14 of the concrete unit and against the injection and venting conduits attached to the hardened concrete surface 14.

My invention also contemplates the securing and anchoring these injection and venting conduits to the concrete poured against the smooth surface 14 of the concrete by any suitable means, preferably by steel straps 16 which are preferably $\frac{1}{2}$ inch wide by $\frac{1}{16}$ inch thick and 3 inches long, attached to the steel angles at about 6 inch centers on alternate legs of the angles by any suitable means, preferably by $\frac{1}{16}$ inch fillet welds

17 for $\frac{1}{2}$ inch along the edges of the straps in contact with the angles. As the concrete shrinks and the joint opening H widens, the small steel angles are rigidly held to the concrete unit in 5 which the anchor straps 16 are embedded, the wire ties used are much weaker and less rigid than the anchor straps 16, thus the wire ties stretch, elongate and break, and an opening occurs along the edges of the angle equal to the 10 opening H of the joint, thus providing an opening for the grout to flow from the injection conduits, out, into, and along the joint opening, and out of the joint opening and into and along the vent conduits until only good grout remains in 15 the joint opening when under full final grout pressure.

My invention also contemplates the making the connections between the open conduits and the pipes by any suitable means that will prevent the 20 entry of mortar into the open conduit or pipe at their connections; I preferably use a $\frac{1}{8}$ inch plate 18 cut to fit the outside dimensions of the section of the end of the conduit, usually cut on a bevel, and attached thereto by any suitable 25 means, preferably by a $\frac{1}{16}$ inch continuous weld 19, the $\frac{1}{8}$ inch plate having a hole 20 in it to fit the outside diameter of the pipe, the pipe inserted into the hole and attached to the plate 18 by any suitable means to prevent the entry of mortar 30 into the conduit or pipe, preferably by a $\frac{1}{16}$ inch continuous weld 21 at the outside surface of contact of the plate and the pipe. The riser pipes, preferably $\frac{1}{2}$ inch in diameter, are connected to the header pipes, preferably 1 inch in diameter 35 by means of T's 22. The header pipes being anchored to the hardened concrete forming the outer surface of the corrugations by means of nails embedded in the concrete, and wire ties similar to the method used in attaching the angle 40 conduits 3 to the concrete surface 14.

In laying out a unit of concrete, I preferably form its border outline along its sides into a continuous succession of equal corrugations 23 except near the sloping surfaces of the structure 45 where the height is reduced to fit in each panel bounded by grout stops 11, the corrugations being formed by projecting the concrete out, in, or at suitable angles from the plane surface strips 14, the width of the smooth surface strips 14 being 50 made equal to the width of the flat projecting area 23. I embed sheet metal strips 11, called grout stops (except at the upstream face where they are usually called water stops), or other suitable material having a U shaped fold 11A 55 along the central portion of their widths, with their folded portion temporarily resting against the contraction joint forming face of the form of the first pour of concrete, then after the form is removed the grout stop is bent out into its final 60 position for embedment in the second pour of concrete, the purpose of these metal strips being to form a stop which will later prevent the grout from escaping from along the contraction joint faces to the exterior surface of the structure for 65 its entire height.

The corrugations 14 and 23 in the formed concrete units C and D of Figures 8 and 9 that are opposite to each other, form a continuous tongue and groove surface throughout practically their length and height except where the corrugations are suppressed to facilitate forming and placing the horizontal grout stops 11; and assuming that the two units C and D have been poured and have hardened, then by closing up the opposite ends F and G of the space E, this space or unit E can be

poured and when it is poured the concrete flows into the vertical groove members against the surfaces 23 and 14, that define the depth of these grooves; and this tongue and groove construction of new units between hardened units results in the new units being locked by these numerous tonguelike keys that enter the hardened units, against any movements except the small vertical and horizontal movements due to shrinkage and temperature change; and after the concrete unit E has also hardened, cooled, and the open joints H grouted, the new units are rigidly locked by these numerous tonguelike keys, against any possible movement whatever from pressures acting in a downstream direction that are caused by the pressure of water or other material against its upstream end, as the units in dam construction are placed transversely across the length of the dam, but the units can be arranged in any other predetermined positions relative to the length and breadth of other kinds of concrete work.

After the concrete has been poured and has set, the forms are removed in the usual manner, and the point ends of the embedded nails are now left protruding from the concrete.

I now bend the protruding ends 24 of the nails A over as indicated in Figure 3; I then place the grout injection and vent conduit and pipe systems and grout stops in position and secure them firmly in place against the hardened face of the concrete units by means of wire ties as indicated in Figure 3, and by fillet welding and threaded connections to connect the portions of these systems together. These materials are preferably installed in units equal to the depth of pour of the concrete with the upper ends of the conduits and pipes left protruding above the top of the next lift or depth of concrete to be poured with the upper ends temporarily plugged and capped to prevent them from becoming clogged during the pouring of concrete. Prior to the pouring of the next lift of concrete above described the edges of the open conduits, preferably angles, are coated with cement mortar or other suitable material and let set to prevent the entrance of mortar into the conduits during the pouring and vibrating of the fresh concrete. After the pouring of the fresh concrete and prior to the time of the concrete's initial set the open conduits are flushed with water to wash out any mortar that may have found its way into the conduits during the concrete pouring operations.

When the fresh concrete above described is first poured and while still in its workable semi-liquid and plastic condition, it is in intimate contact with the contraction joint faces of the seasoned and hardened concrete on either side previously poured, but as it begins to set and harden, considerable rise in temperature in the interior of the mass occurs, and as the process of hardening and setting enters into its final stages, this temperature becomes less and less, and in thick masses of concrete, this heat of hydration of the cement is carried out of the mass by the circulation of cooling water and refrigerating water through preferably one inch pipes embedded in the concrete at the top of each 5 foot lift or pour of concrete with the pipes spaced at about 5 foot centers horizontally, and the resulting drop in temperature produces a reduction or shrinkage in the mass of the concrete and its physical dimensions, thus causing its outer confines to contract towards its center, and those portions originally in contact with the faces of contraction joints pre-

viously poured on either side recedes or pulls away from those faces, leaving an opening H between them, and inasmuch as the open conduits are rigidly anchored by straps 16 in this new contracting concrete, they also recede or pull away from the faces of the concrete units previously poured, so that this receding movement produces two continuous lines of opening, one along each leg of the open conduit to the open space between the faces of the concrete.

When this receding movement between the open conduits and the concrete face occurs, it is resisted only by the wire ties 15 looped over the bent nails A, and these wire ties 15 and loops 25 are straightened, stretched and broken by the relative movement of the two units of concrete, as shown in Figure 2 to accommodate this movement.

In Figures 1, 3, 4, 5, 7, 7A, 8, 9, 10, 12 and 12A, 20 I illustrate a complete fluid grout injection and venting system set up and attached to a formed and hardened face of a contraction joint and held in place by wire ties connected to bent over nails, the head and portion of the shank of 25 which have been previously embedded in the concrete of the first pour, which then hardened.

In Figure 2, I illustrate the condition after the concrete of the third pour has been placed against the hardened concrete face of the first 30 pour, and the concrete of the third pour has hardened, cooled and shrunk away from the hardened face of the first pour of concrete, then the open joint H is ready to receive the grouting material between the two masses of concrete. When the entire concrete structure has 35 thus been completed, I have incorporated in the structure and provided a direct communication for filling the contraction joint opening H with cement grout. This is accomplished by forcing 40 and pumping the grout into the injection pipe connection 4, thence it flows into and along the open injection header conduit 1, and on into and along the injection riser conduits 2, and on up and along the injection riser pipes 6 and 45 into and along the upper pipe header 7, and out the control valve 21 until good grout of proper consistency is discharged, then the control valve 27 is closed, then the grout flows out all along 50 the edges of these conduits 1 and 2 into and along the opening H in the contraction joint directly across the grooves 14 and the corrugations 23, forcing the air, water, and foreign matter in the open joint H ahead of the grout, and to, into and along and down into the vent 55 riser pipes 8 and the lower pipe header 9 and out of the open control valve 26 until good grout of proper consistency is discharged, when the control valve 26 is closed, and the additional grout pumped into the pipe 4 is forced along the 60 opening H directly across the grooves 14 and the corrugations 23, forcing the air, water and foreign matter in the open joint H ahead of the grout, and to, into, and along the riser vent conduits 3 and the vent header conduit 5, on 65 through the vent pipe connection 10, and out of the control valve 28 until good grout of proper consistency is discharged, when the control valve 28 is closed, and the required additional pressure over the entire joint is applied and 70 maintained by closing the control valve 29, or by a pressure control chamber or other suitable means, until the grout has hardened. This illustrates the grouting of the contraction joint shown in Figure 8. In a similar manner the contraction joint shown in Figure 9 is grouted.

and the grout let harden. When this process of grouting has been continued over all the grout panels from bottom to top and from downstream face to upstream face of the dam, the concrete units or masses of concrete are then integrally united into one monolithic structure of concrete.

The same procedure of pumping grouting media of any suitable material under pressure into the bottom header conduits of each of the remaining joints in turn until each system has been entirely filled progressively from the bottom to the top, is followed until all the joints are grouted. The work of grouting can be performed at any time after the concrete has hardened upon both sides of the joint or joints, but the best results are obtained when the concrete has a temperature below normal and has attained maximum contraction as in winter or by cooling or refrigeration as herein described.

When using cement grout, I preferably force water and air and water mixed under pressure through each space that forms the contraction joint opening H, washing out laitance and other deleterious materials that prevent the bonding of the grout to the concrete faces of the open joint H. After the washing out of the joint, I fill all the open joints H full of clear water for several days before starting to introduce the grout, as this fills the interstices of the adjoining concrete with water, and moistens all surfaces which the grout is required to bond, and insures that the grout will reach all portions of the voids in the open joint with its proper free flowing consistency, which it would not otherwise retain were it progressively coming in contact with dry concrete and losing its moisture content by absorption therein.

From the foregoing it will be observed that the filling or bonding mixture is introduced directly into the open joint along predetermined lines progressively from the bottom of the structure towards the top, and the venting of the open joint along predetermined lines parallel to, opposite to, between and above the grout injection lines, so that the bonding mixture must pass directly through and across the open joint between the injection and vent systems before it can be discharged out through the vent system, thus insuring free escape of the air upwards and the water out of the joint from the ascending bonding mixture, avoiding any possibility of entrapped or imprisoned air, gases, water, inert grout and laitance, or other poor quality bonding mixture, forming pockets or gaps where bonding could not otherwise occur; that the conduit system supplying the predetermined lines of entry into the joint and lines of vent out of the joint are directly in contact and open to the joint opening along their entire lengths, on each side of the open conduits, thereby making certain the delivery of the bonding mixture to all parts of the joint surfaces to be bonded.

It is to be understood that the form of my invention herewith shown and described is to be taken as a preferred example of the same, and

though it refers particularly to contraction joint openings as being the type that are in a vertical plane, the invention can be equally used in any contraction joint in any other plane, including

- 5 warped surfaces, and in any type of structure to which the principle of the invention can be applied, and that variations relative to the material, size, shape and arrangement of the elements involved can be resorted to without departing from 10 the spirit of the invention or the scope of the subjoined claims.

Having described my invention, what I claim as new and desire to secure by Letters Patent is:

1. Apparatus for grouting the contraction joint 15 between two concrete units, comprising open header and open riser conduits in a grout injection system and a grout venting system, the grout injection conduits being in the form of a channel with the edges of the open side thereof positioned 20 against the contraction joint face of the first poured unit of hardened concrete, means yieldingly secured to said conduits and to the contraction joint face of the first poured unit of hardened concrete for enabling an opening to form between said edges and face by the shrinkage of the concrete whereby grout is permitted to flow into the contraction joint, means associated with said conduits for fixing the same in the second poured unit of concrete, means connecting the ends of said open conduits for the injection and venting of grout in these open conduits, and means for closing the ends of the open contraction joints.

2. The invention as set forth in claim 1, where- 35 in the said means connecting the ends of said open conduits comprise injection and vent riser pipes connected to the ends of the open injection and vent riser conduits respectively and leading to an upper injection header pipe and a lower vent header pipe respectively and thence these header pipes lead to the surface of the finished concrete structure.

3. Apparatus for grouting the contraction joint 45 between the two concrete units, comprising means for closing the ends of the contraction joint, a lower grout injection open header conduit and connected thereto a plurality of open grout injection riser conduits and located opposite to and approximately half way between and above these 50 injection conduits, a plurality of open grout vent riser conduits and connected thereto an upper grout vent open header conduit, means for flexibly holding the open side of said conduits against the smooth face of the concrete unit first poured, pipe connections from said open header conduits lead- 55 ing to the surface of the concrete structure and including a plurality of small pipes connecting from the upper ends of the grout injection riser conduits to an upper header pipe that leads to the surface of the concrete structure; and a plu- 60 rality of small pipes connecting from the lower ends of the grout vent riser conduits to a lower header pipe that leads to the surface of the concrete structure.

RAY L. ALLIN.
